UNITED STATES PATENT OFFICE.

AMOS S. HEFFRON, OF PHILADELPHIA, PENNSYLVANIA.

STIFF-LEG DERRICK.

Application filed June 25, 1921. Serial No. 480,410.

To all whom it may concern:

Be it known that I, AMOS S. HEFFRON, a citizen of the United States, residing at Philadelphia, in the county of Philadelphia and State of Pennsylvania, have invented certain new and useful Improvements in Stiff-Leg Derricks, of which the following is a specification.

One object of my invention is to provide an improved stiff leg derrick which can be more easily and conveniently used than derricks of like character made previously to my invention.

Another object of my invention is to provide a stiff leg derrick in which its boom can operate at any position within a radius of practically 360° and at the same time the derrick will be entirely self-supporting without the use of any guy tackle.

20 A further object is to so construct my improved derrick that it can be quickly and easily assembled and erected and provide a stiff leg derrick which is entirely self-supporting and free of guy tackle.

25 Another object is to so construct my improved derrick that it can be used more advantageously owing to the arrangement of its parts so that it can be bodily shifted without the necessity of loosening or changing any guy tackle and as such it can be advantageously used in the erection of buildings or other structures.

30 Another object is to make my improved derrick of a durable and comparatively simple construction and so that the parts will be firmly held in operative position but can be easily disassembled.

35 A still further object is to provide a mounting for the operating cables so that they will not interfere with the swinging action of the boom and will not be in the road of any material which is being lifted and conveyed from one position to another; the outlet or lead of the cables from the derrick to the hoisting apparatus being located in a convenient position most desirable for the successful operation of the derrick.

40 These objects, and other advantageous ends which will be described hereinafter, I attain in the following manner, reference being had to the accompanying drawings in which—

45 Figure 1 is a perspective view showing my improved derrick in an operating position; said figure illustrating in dotted lines the possible changing of the positions of cer-

tain of the elements to suit various requirements,

50 Figure 2 is a perspective view showing how most of the parts of my improved derrick can be assembled when the structure is lying flat on the ground as indicated by the full lines; said figure also illustrating in dotted lines how certain of the parts can be swung into a position prior to the tipping of the structure into an upright position.

55 Figure 3 is a perspective view showing the structure after having been tipped into an upright position and prior to the attachment of the boom,

60 Figure 4 is a top plan view of my improved derrick showing it in an operative position with one of the lateral stiff legs having been detached from the front transverse sill and swung into a position to permit the boom to swing in a path between the front and rear sills at one side of the structure,

65 Figure 5 is a view of the same general character as that shown in Figure 4 illustrating the other of the lateral stiff legs having been detached from the front sill and swung into a position to permit the boom to swing into a position between the front and rear sills at the opposite side of the structure,

70 Figure 6 is a fragmentary elevation showing the arrangement of the front or transverse sill having extensions which can be moved to increase the length of the front sill and also illustrating rollers moved into a position to facilitate the movement of the structure, said figure being viewed from the rear of the sill,

75 Figure 7 is a view of the same general character as shown in Figure 6 illustrating the sill in its normal position with the extensions having been moved into their inner positions when not desired for use,

80 Figure 8 is an enlarged fragmentary view of one end of the structure shown in Figure 7,

85 Figure 9 is an enlarged fragmentary elevation of a portion of the front sill viewed from the rear illustrating the cable controlling means and the mounting for the mast,

90 Figure 10 is a section taken on the line 10—10 of Figure 9,

95 Figure 11 is an enlarged front elevation of the mast; the intermediate portion of the same being broken away,

Figure 12 is a side elevation of said mast, Figure 13 is a rear view of a portion of said mast, and

Figure 14 is a fragmentary section taken on the line 14—14 of Figure 4.

Referring to the drawings, my improved derrick includes a front transversely extending sill 15 which is made continuous from one end to the other and includes two channels 16 and 17 which are spaced apart from front to rear. Top and bottom plates 18 and 19 are secured to the tops and bottoms of the channels 16 and 17 so as to enclose the space 20 between the channels with the exception that the space 20 is open at its opposite ends for a purpose hereinafter described. Two attachment or fish plates 18^a and 19^a are secured respectively to the top and bottom of the front sill 15 and have portions which project forwardly and rearwardly of the front and rear sides of said sill; said attachment plates being preferably located centrally between the opposite ends of the sill 15. A mast 21, which is clearly shown in detail in Figures 11, 12 and 13 and also illustrated in its assembled position in Figures 9 and 10, includes two upright standards 22 in the form of channels which are spaced apart to provide an inner chamber 23. A filler sleeve 24 is secured by bolts between the standards 22 adjacent their rear ends; said filler sleeve having a projecting pivot nipple 24^a which extends downwardly through holes 25 and 26 in the attachment plate 18^a and top plate 18 respectively as clearly shown in Figure 10; said sleeve having its lower surface 27 bearing on the top surface of the plate 18^a. A filler plate 28 is secured to the top of the sill 15 above the attachment plate 18^a and has a hole 29 providing a lateral bearing for the side of the sleeve immediately above the surface 29.

The filler sleeve 24 has an annular groove 30 in which extend the inner edge portions of locking plates 31; said locking plates, after their inner portions have been inserted within the groove 30 at positions opposed to each other, being secured to the top sill above the filler plate 28 by bolts 32. Thus the filler sleeve is free to rotate but is locked against vertical movement to the sill 15. The nipple 24^a extends into the space 20 formed within the sill 15 and the inner passage 33 of said filler sleeve 24 communicates with the space 20 for a purpose hereinafter described. The filler sleeve 24 has a pair of ears 34 which project outwardly and form a pivotal connection for the lower end 60 of the boom 35; said boom being pivotally connected to said ears by a bolt or rod 36.

The upper end of the mast 21 has a terminal block 37 secured between the channels 22; said terminal block terminating in a

sleeve 38 which projects above the tops of the standards 22. The sleeve 38 has a portion 38^a of reduced diameter providing a shoulder 39. A head 40 is secured to the portion 38^a of the sleeve 38 and abuts the shoulder 39. This head has ears 41 which are spaced apart and a pivot bolt 42 extends through the ears 41 and forms a bearing for two grooved pulley wheels 43 and 44 which are preferably made of different diameters, as clearly shown in Figures 11, 12 and 13. The terminal block 37 and its sleeve portion 38 have an axial passage 45 which communicates with the chamber 23 between the channels 22.

The rear channel 17 of the front sill 15, as shown in Figures 9 and 10, has an aperture 46. Directly in line with this aperture 46 and to the rear of the channel 17 are mounted two pairs of grooved pulley wheels 47 and 48; said pulley wheels being rotatably mounted on pivot pins 49 having rotatable bearings in brackets 50 and 51; the pivot pins 49 having heads in engagement with the upper bracket 50 so that the pins can be readily removed if desired. A bracket 52 within the space 20 of the sill 15 supports two pulley wheels 53 and 54. The pulley wheels 47 and 48 are adapted to rotate in horizontal planes and the pulley wheels 53 and 54 rotate in vertical planes. The pulley wheel 53 is preferably made of smaller diameter than the pulley wheel 54 so that portions of the peripheral surfaces are directly under the passage 33 of the nipple 24^a. Each of the pairs 47 and 48 includes a small wheel and a large wheel as shown in Figure 7; the small wheel of the pair 47 being directly over the large wheel of the pair 48, and vice versa the large wheel of the pair 47 being positioned over the smaller wheel of the pair 48. This arrangement of wheels is preferred to space the operating cables in the mast and to prevent the upper cable dropping between the pulleys 48.

The front sill 15 at positions adjacent its ends and opposite both sides of the mast 21 has pairs of brackets 55 and 56 secured thereto; the brackets of each pair being spaced apart from front to rear. A lateral stiff leg 57 has its lower end detachably secured between the pair of brackets 56 by a bolt 58; said bolt extending through the brackets 56 and through a hole in the lower end of the stiff leg 57. The upper end of the leg 57 has an angular portion 59 provided with a hole through which extends the sleeve 38 of the mast 21. A second lateral stiff leg 60 has its lower end secured between the brackets 55 by a bolt 61; said bolt passing through holes in the brackets and through a hole in the bottom of the leg 60. The leg 60 at its

upper end has an angular portion 62 which has a hole through which the sleeve 38 of the mast 21 extends; said angular portion 62 overlapping the angular portion 59 of the stiff leg 57.

5 A rear sill 63 has one end pivotally connected to the projecting portions of the attachment plates 18^a and 19^a; said pivotal connection being through the medium of a removable pin or bolt 64 which passes through the attachment plates and through the end of the sill 63. Thus the rear sill under certain conditions can swing on the bolt 64 as a pivot in the plane of the front sill.

10 The opposite end of the rear sill has a pair of brackets 65 secured thereto between which is secured the lower end of a rear stiff leg or brace 66; the connection between the leg 66 and the brackets 65 being through the medium of a bolt 67 which extends through holes in the brackets 65 and through a hole in the lower end of the leg 66. The upper end of the leg 66 has an angular extension 68 provided with a hole through which the sleeve 38 of the mast extends; said extension 68 overlapping the extension 62 of the stiff leg 60; the length of the extension 68 being such as to permit either of the lateral stiff legs 57 and 60 to swing thereunder when their lower ends are detached from the front sill by removing the bolts 58 or 61. Figure 1 shows in dotted lines as indicated at α either one of the lateral stiff legs having been detached from the front sill and swung into a position under the extension 68 so that the lower end of the lateral stiff leg will be positioned directly above the top surface of the rear sill 63.

15 The operating cables 69 and 70 lead to the derrick between one side of the rear sill 63 and the front sill 15 preferably at a slant as shown in Figures 4 and 5. The cable 69 passes between the wheels 47 and then through the aperture 46 into the space 20 of the front sill and then under the wheel 53 and upwardly through the passage 33 of the nipple 24^a and sleeve 24, through the chamber 23 between the standards 22, then through the passage 45 of the block 37 and sleeve 38, then over the wheel 43, then over a guide pulley 71 in the outer end of the boom 35, after which it passes around the wheels of pulley blocks 72 and 73 and is attached to the ear 74 on the pulley block 72; said pulley block 72 having a hoisting device, such as the hook 75, mounted thereon. The cable 70 passes between the wheels 48 then through the aperture 46 into the space 20 of the front sill 15, then around the wheel 54, upwardly through the passage 33 of the nipple 24^a and sleeve 24, then upwardly through the chamber 23 and passage 45 around the wheel 44, then over a pulley

block 76 which is linked to the boom, then rearwardly over a pulley block 77 which is linked to an eye 78 on the head 40 and then forwardly and is attached to the pulley block 76. It is thus obvious that when the cable 69 is pulled due to the action of the hoisting apparatus, the lifting device will be operated and when the cable 70 is operated the boom will be swung on its pivot 36 into various angular positions.

20 Auxiliary extensions 79 slidably fit within the space 20 in the front sill 15 and can be withdrawn to provide a front sill of an increased length and bearing surface as shown in Figure 6. These auxiliary extensions adjacent their outer ends have members 80 slideable vertically therein within guideways 81. The members 80 at their lower ends support rollers 82 which can be moved downwardly into engagement with a floor or supporting structure to facilitate the moving of the derrick from one place to another. Pins 83 can be inserted through holes in the extension 79 and in the members 80 so as to hold the rollers in their extended positions as shown in Figure 6 or in their retracted positions as shown in Figure 7; it merely being necessary to remove the pins 83 from one of the holes in the extension and re-insert the pin in another one of said holes; the holes in the extension respectively registering with the hole in the member 80 when the member is either in its projected position or its retracted position.

25 In the operation of the derrick, the boom may be swung into any position in front of the sill 15 and if it is necessary that the boom should swing at a greater radius, such for example as between the front and rear sills at either side of the rear sill, it is only necessary to remove the pivot rod or bolt 58 or 61 of the lateral stiff leg adjacent the side in which it is desired to swing the boom, and to move said stiff leg into a position under the extension 68 of the rear leg 66 and the boom can then be swung over the front sill into any position between the front sill and the rear leg. In Figure 4, I have illustrated the stiff leg 60 having been detached and the boom 35 swung into a position between the front sill and the rear sill on one side of the structure. If it is desired to attach the stiff leg 60 to the front sill and to release the lateral stiff leg 57 and swing the latter into a position under the extension 68 of the leg 66, then the boom, as shown in Figure 5, can be swung into any position between the front sill and the opposite side of the leg 66. It will be noted that this action can take place without the use of any guy tackle and furthermore that there is always one of the lateral stiff legs in its connected position with the front sill therefore the derrick is self-

supporting even when the boom swings into a position between the front and rear sills. It will be further noted that this arrangement permits the boom to swing within a radius of substantially 360° so as to increase the field of action on a derrick of this type.

By providing the attachment plates so as to have portions projecting forwardly and rearwardly of the front sill if it is desired the rear sill 63 can be attached at the opposite side as shown in dotted lines at 63^a in Figure 1.

By having the arrangement of pulleys and the construction of mast as above described, the operating cables can be led to the derrick and passed in such manner through the chamber 23, passages 33 and 45 and over the pulley wheels so that there are no projecting cables and at the same time the mast can swing with the action of the boom without fouling or becoming entangled, as is obvious from the construction shown.

The construction is such as shown in Figures 2 and 3 as to facilitate the assembly and erection of the derrick. The parts as shown in Figure 2 can be attached while the structure is flat upon the ground and the rear sill and stiff leg 66 can afterwards be swung into an upright position and then the whole device can be tipped into the position shown in Figure 3, after which the boom can be quickly attached, together with the cables and if desired the cables can be inserted while the structure is flat upon the ground and before it is tipped.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A derrick including a transversely extending front sill; a rear sill pivotally connected to the front sill; a mast in pivotal connection with the front sill; a boom pivotally connected to said mast; a stiff leg pivotally connected to said mast and connected to said rear sill and arranged to swing therewith; attaching means for pivoting said rear sill forward of said front sill; and lateral stiff legs pivotally secured with respect to the mast and detachably secured to the front sill at opposite sides of the mast whereby either of said stiff legs can be detached from the front sill and moved into position to permit the boom to swing to the

rear of the front sill, and the rear sill to be swung and mounted forward of the front sill; substantially as described.

2. A derrick having a transversely extending supporting sill with a mast thereon; lateral legs slanting from said mast to said sill; an auxiliary extension slidably mounted on each end of said supporting sill; and supporting members adjustably connected to said extensions and having rollers thereon to facilitate moving said derrick; substantially as described.

3. A derrick having a transversely extending sill; a mast pivotally mounted thereon; a pair of lateral stiff legs pivotally secured to said mast and detachably secured to said sill; auxiliary extensions slidably mounted in said sill and being expandable beyond said legs; and adjustable supporting means mounted beneath said extensions to facilitate moving the derrick, substantially as described.

4. A derrick including a transversely extending front sill; a rear sill connected to the front sill; attaching means for mounting said rear sill forward of the front sill; a mast pivotally mounted on said front sill; a boom swingably mounted on said mast; a rear leg connected to said mast and rear sill; and lateral stiff legs pivotally secured with respect to the mast and detachably secured to the front sill at opposite sides of the mast, the pivotal connections of the stiff legs to the mast being so constructed that either one of said stiff legs may be detached from the front sill and moved in a position beneath the rear leg and permit the boom to swing rearward to said rear leg, substantially as described.

5. A derrick including a transversely extending front sill; a mast mounted on said sill; a rear sill in pivotal connection with said front sill and adapted to swing in the plane of said front sill; attaching means for pivoting said rear sill forward of said front sill; a stiff leg pivotally connected to the upper portion of said mast and to the outer portion of said rear sill and arranged to swing with said rear sill; and a second stiff leg pivotally mounted on said mast and arranged to permit swinging of the first leg over the second leg, for pivoting said rear sill on said attaching means forward of said front sill; substantially as described.

6. A derrick including a front sill; a mast pivotally mounted on said sill; means for supporting said mast; vertical pulley wheels disposed beneath said mast; a pair of pulley wheels including a large and small pulley wheel mounted adjacent and transverse to said vertical wheels and arranged edge to edge; and another pair of similar oppositely disposed pulley wheels arranged beneath said first pair of pulley wheels;

and cables connected to said boom, one of said cables extending between one pair of pulley wheels and over one vertical pulley wheel, and another of said cables extending between the other pair of said pulley wheels and over the other vertical pulley wheel, substantially as described.

In testimony whereof I have signed my name to this specification in the presence of two subscribing witnesses.

AMOS S. HEFFRON.
